UNITED STATES PATENT OFFICE.

LEANDER W. BOYNTON, OF HARTFORD, CONNECTICUT.

SPRING FABRIC.

SPECIFICATION forming part of Letters Patent No. 284,717, dated September 11, 1883.

Application filed December 22, 1882. (No model.)

To all whom it may concern:

Be it known that I, LEANDER W. BOYNTON, of Hartford, in the county of Hartford and State of Connecticut, have invented a new and useful Improvement in Spring Fabrics, of which the following is a specification and description.

The object of my invention is to provide a cheap, light, and durable spring fabric in which all the elastic qualities of the springs shall be utilized to the best advantage, and in which the springs themselves shall form a great part of the horizontal surface of the fabric; and I accomplish this by the mechanism substantially as hereinafter described, and illustrated in the accompanying drawings, in which—

Figure I is a plan view of a spring-bed, showing an adaptation of my improved spring fabric to that purpose. Fig. II is a side elevation of the same; and Fig. III is a vertical section at line A of Fig. I, showing means for securing the end rail in a stationary position.

In the drawings, 1 represents the two side rails, and 2 the end rails, of a spring-bed, secured at their ends to the rails 1 by a casting, as 3, and bolts or screws inserted through the casting and turned into each side and end rail near or at their ends. These castings may be of any desired form or pattern, and may be ornamented to any desired degree.

The springs 4, I make of straight steel wire of suitable size—say of No. 10 or No. 12 gage, according to the strength desired—and I give it a general corrugated or serpentine form, with the corrugations of, say, approximately an inch in depth, as giving a good result. This form may be given to the wire very conveniently by passing it, either directly from the coil or cut into desired lengths, between two geared or cog wheels, whose teeth or cogs are of suitable form and distances apart to give the wire the general corrugated or serpentine form, as shown in Fig. I. If the wire is given this form in continuous lengths, it is then cut in suitable lengths to extend, preferably, the entire width of the fabric from side to side, and each end of each length bent around to form, substantially, a ring or loop, as shown in Fig. I.

When this improved fabric is to be used in the manufacture of portable spring-beds, a

strap or flat band of metal, as iron, and shown at 6, is secured to the top of each end rail, 2, the edge of said band overlying the inner side of the rail a little, as shown at Fig. I, in which the dotted line indicates the inner side of the rail, and the inner overlying edge of each band is perforated with holes 7, at the same distances apart as the distances between the corrugations in the wire 4. These series of corrugated or serpentine wires or springs 4 are secured taut and in a horizontal plane by a series of short wires, 5, bent somewhat into the form of a hook at each end, as shown clearly in Fig. II, and each is hooked at one end into one of the corrugations of one wire or spring 4, and at the other end into the opposite corrugation of the next wire or spring 4, as shown clearly in Fig. I, and at each end of the short wires or links 5 are drawn taut and hooked into the holes 7 in each end band, 6.

In forming a spring-bed a series of the wires or springs 4 are used, a few inches apart, as shown clearly in Fig. I, and they may be conveniently secured in place, or the bed "set up," by first securing only one of the bands 6 in place on one end, 2, and hooking the wires or links 5 into the holes 7 in said band, and then hooking the other ends of those wires or links into the alternate bends or corrugations of a wire or spring, 4, or into those bends or corrugations which extend toward those wires or links 5 which are hooked into the holes 7. Another second series of short wires or links 5 are then hooked at one end into the other alternate bands, or into those which extend in the opposite direction from those first mentioned, and the other ends of said second series of short wires or links 5 are hooked into the bands or corrugations of another wire or spring 4, and so on, this operation of hooking on a series of short wires or links 5 and then a corrugated wire or spring 4 being continued the entire length of the bed. Short wires or links 5 are also hooked from the ring or loop at the end of each wire or spring 4 to that of the next, to secure them all properly in line at each edge of the fabric, as shown clearly in Fig. I; and when the wires or springs have been all thus linked together in place the free ends of the last row or series of short wires or links 5 are hooked into the holes 7 of the re-

maining band 6 before the latter is secured to the end 2 of the frame. Any suitable device—as three or four small screw-clamps—may then be attached to the rail 2 along its length and 5 along the unsecured band 6, and by turning the screw of each clamp the whole series of connected wires, or the whole fabric, together with the unsecured band 6, are drawn taut, and the latter secured into place to the top of 10 the end rail, 2.]

The wires or springs 4 may be tempered, if desired, to any degree of hardness or spring temper, although a good and durable spring fabric may be made of ordinary untempered 15 steel wire; and these wires, instead of extending across the entire width of the fabric, may extend only partially across, and two or more of them be placed together endwise, with loops or rings formed at their ends, and connected 20 together by a link or wire 5, as shown at B. The operation would, however, in that case be precisely the same as that hereinbefore described, and I prefer to make them to extend the whole width of the fabric, as being more 25 convenient to manipulate and less expensive.

By making the springs 4 as above described, I am enabled to utilize the elastic qualities of the wire in every direction, both lengthwise 30 of the wire and across the fabric and transverse- ly across the wire and lengthwise the fabric; and as each wire or spring 4 operates elasti- cally in direct connection with the adjacent ones along each side of it, the elastic qualities 35 of the wires or springs are evenly and uni- formly distributed over a comparatively large horizontal area.

This fabric may be made cheaply and quickly, and, owing to this large horizontal distribution of the elastic properties of the wire, a 40 comparatively small quantity, in weight, of metal is required.

When this fabric is used in the construction of beds, it is evident that only the two end rails, 2, need be used, with a band, 6, secured 45 to each, so that they may be shipped by roll-

ing the end rails and the wires, all secured together, into a roll, and the end rails be afterward secured to the side rails, or to the side rails of a bedstead, in any desired manner, with the connected wires stretched horizon- 50 tally and taut between.

I am aware that a spring fabric has heretofore been made containing a series of transverse wires bent in an angular form, and in which each wire between each two adjacent angles 55 was straight, as shown in patent to A. Youngs, November 16, 1875, instead of curved, as shown in my construction; and I do not claim a fabric in which any portion of each transverse spring is not a continuous curve or a series of con- 60 tinuous curves in opposite directions, alter- nating with each other in the same plane. These springs, having this series of continuous alternating curves in the same plane, have a much better elastic quality, are stronger and 65 more durable, and are more uniform in their action, whereas springs any part of which are made straight are apt to become bent and set, and are then worthless for any purpose re- 70 quiring elastic qualities.

Instead of the inner edge of the bands 6 be- ing perforated and the short wires or links 5 hooking into said perforations 7, the wires or links at each end of the fabric might extend out over the band and hook over its outer 75 edge, as shown at C, without departing in the least from the operation of the invention.

Having thus described my invention, what I claim as new is—

An improved spring fabric consisting of a 80 series of serpentine springs, each of which is formed by alternate curves to and fro in the same plane along its entire length, and a series of hooked wires or links connecting the curves in each said spring with those of the next ad- 85 jacent spring, substantially as described.

LEANDER W. BOYNTON.
